UNITED STATES PATENT OFFICE

1,924,676

HAIR CLIPPERS

David B. Brown, Bellingham, Wash., assignor to
Wahl Clipper Corporation, Sterling, Ill., a cor-
poration of Illinois

Application May 16, 1930. Serial No. 452,975

7 Claims. (Cl. 30—1)

My invention relates to hair clippers particularly of the alternating current electro-magnetic type, but not limited especially thereto.

5 It is the principal purpose of this invention to provide in a clipper of this type a novel means for controlling the position of the stationary blade so that it can be advanced or retracted by the operator.

10 A further and more specific purpose of this invention is to provide, in connection with the novel means above referred to, means to prevent any rattling of the stationary blade due to the rapid rate of vibration to which the machine is subjected.

15 A further object of the invention is to provide also a device of this character in which the adjustment of the stationary blade is accomplished through the medium of a simple action 20 that permits a relatively long movement of the operator's finger-piece in adjusting the blade for a short movement of the blade itself thus making it possible to obtain very fine or micrometer adjustments without any particularly delicate operation of the finger-piece.

25 I will describe one form which the invention will take by reference to the accompanying drawing wherein the preferred form of the invention is shown. It is obvious, of course, that the disclosure is illustrative only and is not to be taken as limiting the invention except in so far as it is limited by the claims.

In the drawing—

30 Fig. 1 is a side view of a clipper equipped with my blade adjusting device;

Fig. 2 is a bottom view of the clipper;

Fig. 3 is a fragmentary section taken longitudinally through the clipper;

40 Fig. 4 is a detailed section on the line 4—4 of Fig. 3; and

Fig. 5 is a section on the line 5—5 of Fig. 3.

Referring now in detail to the drawing, I show at 10 a clipper provided with a so-called stationary blade 11 and a movable blade 12 which movable blade is connected by the elements 13 and 14 to a vibratory armature 15 in a well known manner. Means for vibrating the armature 15 forms no part of the present invention and may be of any well known type such as that shown for instance in the patent to Leo J. Wahl, Patent No. 1,558,729, issued October 27, 1925. The movable blade is yieldingly pressed toward the stationary blade by the connecting members 13 and 14. The stationary blade is mounted by means of the screws 16 and 17 upon a member 18 which

has bevelled edges as indicated at 19 and 20 (see Fig. 4) fitting in a corresponding groove at 21 of the casing 10.

In this way the member 18 and with it the stationary blade may be advanced and retracted by sliding along the groove provided in the casing. As a means of causing this sliding action, I provide connecting means consisting of the spring 22 which is secured as by means of the rivet 23 to the member 18 and which has its other end secured by means of the rivet 24 to an operating lever 25 pivoted on the casing by means of the stud 26 and having the finger-piece 27 turned up along side the casing at the end opposite the pivot 26. The member 25 may be slightly bowed as shown in Fig. 5 if desired so as to frictionally engage at 28 and 29 with the bottom of the casing and thus aid in maintaining the stationary blade in any adjusted position without the necessity of the operator holding the finger-piece 27.

From the above description, it will be clear that by moving the lever 25 forward or backward the stationary blade will be advanced or retracted and, owing to the relatively great distance of the finger-piece 27 from the pivot 26 in comparison with the distance from the pivot 24 of the spring 22 to the pivot 26, a very fine adjustment of the stationary blade can be made without any delicate operation of the finger-piece.

The spring 22 in addition to its function of serving as the operating action from the lever to the stationary blade also performs a very important function in the operation of the clipper with this blade. This function lies in holding the bevelled edges of the member 18 downwardly against the corresponding bearing surfaces in the casing. The spring 22 is so formed that regardless of the position of the stationary blade it is always under tension due to its curvature so that it is tending to press outwardly toward the stationary blade and thus wedge the bevelled edges 19 and 20 tightly into their bearings and prevent any rattling due to the vibration. At the other end the stationary blade is, of course, subjected to a similar pressure by the movable blade, and the cooperation of these two pressures in forcing the member 18 tightly into its bearings eliminates the rattling that would otherwise be caused due to vibration.

Another novel feature lies in the provision of means whereby the lengths of stroke of the lever 25 may be limited so that it cannot exert too great a strain on the connecting member 22 or force the stationary blade too far in either direc-

tion. This means consists of the inturned projection 30 provided at the upper end of the finger-piece 27 which projection is bevelled as shown in dotted lines in Fig. 2 and is so situated that at one limit of its movement one corner will engage with the side wall of the casing while at the other limit of its movement the opposite corner will engage in the same fashion thus making it impossible to move the stationary blade beyond a certain well defined limit and thereby causing damage to the operating mechanism or the bearing surface between the stationary and movable blades.

From the above description, it is thought that the construction and operation of this device will be clear to those skilled in this art and the advantages thereof readily apparent.

Having thus described my invention, what I claim as new and desire to secure by Letters Patent is:

1. In a clipper having a casing, a movable blade, a stationary blade, mounting means on which said stationary blade is adjustable to vary its projection beyond the front edge of the movable blade, an operating lever mounted on the casing in spaced relation to the stationary blade, and a curved spring member directly connecting said lever and blade for adjusting the blade and pressing it against its mounting means.
2. In a clipper having a casing, a movable blade a stationary blade, mounting means on which said stationary blade is adjustable to vary its projection beyond the front edge of the movable blade, an operating lever mounted on the casing in spaced relation to the stationary blade, and means directly connecting said lever and blade for adjusting the blade, said means pressing said blade into its bearing on said mounting means in all positions of adjustment of said stationary blade, said mounting means and blade having cooperating inclined bearing surfaces.
3. In a clipper having a casing, a movable blade a stationary blade, mounting means on which said stationary blade is adjustable to vary its projection beyond the front edge of the movable blade, an operating lever mounted on the casing in spaced relation to the stationary blade, and a curved spring member directly connecting said lever and blade for adjusting the blade, said mounting means and stationary blade having inclined bearing surfaces, and said spring member

pressing outwardly against said blade to aid in maintaining a tight fit between said bearing surfaces.

4. In a clipper having a casing, a movable blade a stationary blade, mounting means on which said stationary blade is adjustable to vary its projection beyond the front edge of the movable blade, an operating lever mounted on the casing in spaced relation to the stationary blade, and means directly connecting said lever and blade for adjusting the blade, said lever having a finger piece remote from its connection with the casing and said means for adjusting said blade, and means on said finger piece cooperating with the casing to limit the range of movement of said lever.

5. In a clipper having a casing and a movable cutting blade and means for varying the closeness of cut of the clipper comprising an adjustable plate movably carried by the casing whereby to vary its position relative to the front edge of the movable blade, an operating lever mounted on the casing in spaced relation to the adjustable plate, and a curved spring member directly connecting said lever and plate for moving said plate forward and back in response to corresponding movements of said lever, said spring member being under a bending stress in all positions thereof whereby to prevent vibration of said plate.

6. In a clipper having a casing, a movable blade, a stationary blade, mounting means on which said stationary blade is adjustable to vary its projection beyond the front edge of the movable blade, an operating lever mounted on the casing in spaced relation to the stationary blade, and means connecting said lever and blade for adjusting the blade, and means on said lever co-operating with the casing to limit the range of movement of said lever.

7. In a clipper having a casing, a movable blade, a stationary blade, mounting means on which said stationary blade is adjustable to vary its projection beyond the front edge of the movable blade, an operating lever mounted on the casing in spaced relation to the stationary blade, and means directly connecting said lever and blade for adjusting the blade, and means on said lever co-operating with the casing to limit the range of movement of said lever.
